UNITED STATES PATENT OFFICE.

PAUL SUMBLER, OF PLATTSBURG, NEW YORK, ASSIGNOR OF FIFTY ONE-HUNDREDTHS TO HIMSELF, THIRTY-THREE AND ONE-THIRD ONE-HUNDREDTHS TO MARCUS J. CLOW, AND SIXTEEN AND TWO-THIRDS ONE-HUNDREDTHS TO CHARLES F. HUNTER, ALL OF PLATTSBURG, NEW YORK.

GAS-ENGINE.

1,101,352.

Specification of Letters Patent. Patented June 23, 1914.

Application filed February 28, 1913. Serial No. 751,281.

To all whom it may concern:

Be it known that I, PAUL SUMBLER, a citizen of the United States, and a resident of Plattsburg, in the county of Clinton and State of New York, have invented a new and Improved Gas-Engine, of which the following is a full, clear, and exact description.

This invention relates to gas engines designed to operate on what is known as the Otto or Beau de Rochas cycle (more commonly described as four-cycle engines) which consist of one or more cylinders acting on reciprocating pistons to produce rotation of crank shaft, but I would have it understood that the essential features of this invention need not be so limited in their application.

Among the objects of the invention is to devise a means for operating the engine valves, the ignition timer and other necessary auxiliary working parts of the engine which will do away with the use of spur, bevel, spiral or other toothed gearing in the said engine, such gearing being expensive and difficult to manufacture and assemble properly, and tending to run noisily and inefficiently.

A further object of the invention is to render it more simple to take down and assemble an engine for repairs or inspection and make the engine lighter and more compact, a distinct advantage in motor vehicle or aeroplane engines, although its use is not limited to such engines, but is practicable and advantageous for stationary engines using natural or artificial gas or vaporized liquid fuel oils for motive power.

The foregoing and other objects of the invention will hereinafter be more fully described and claimed and illustrated in the drawings forming a part of this specification in which like characters of reference indicate corresponding parts in all the views and in which—

Figure 1 is an elevation illustrative of a preferred embodiment of the invention applied to a four-cylinder four-cycle engine as it may be applied to an automobile, the engine casing and other parts being broken away; Fig. 2 is a detail in elevation and partly in section substantially on the broken line 2—2 of Figs. 1 and 3; Fig. 3 is a plan view of the grooved member shown in Fig.

2; Fig. 4 is a sectional view on line 4—4 of Fig. 3; Fig. 5 is a view of the ignition timer, partly in elevation and partly in section, on the line 5—5 of Fig. 6; Fig. 6 is a transverse view of the same, partly in elevation and partly in section, on the line 6—6 of Fig. 5; and Fig. 7 is a development of the inner surface of one of the parts of the ignition timer, the same indicating the arrangement of the various contact points.

The several parts of this invention may be made of any suitable materials and the relative sizes and proportions, as well as the general design of the apparatus, may be varied to a considerable extent without departing from the spirit of the invention hereinafter specifically set forth and claimed.

As is usual in internal combustion engines of the four-cycle type, there is provided one admission of hydrocarbon and one ignition with respect to each cylinder during each two rotations of the main or crank shaft. To this end, therefore, as engines of this type are usually built, it is necessary to employ a considerable amount of auxiliary mechanism such as cams, reduction gearing or the like in order to secure the proper timing of the valve and other mechanism of the engine from the main shaft. By this invention, however, I provide a peculiar form of actuating means which may assume various forms but which co-operates directly with the shaft, or a member secured to the shaft, so as to produce an irregular or intermittent operation of any desired part of the engine from the shaft while the latter is making its regular rotations. To this end, therefore, I provide an annular member which is arranged concentrically of the shaft and either secured thereto for rotation therewith or mounted in a relatively stationary position, such annular member, however, being provided with a plurality of substantially parallel runways in which an actuator is adapted to operate in alternation, the actuator being shiftable laterally of the annular member from runway to runway, or longitudinally of the axis of the shaft, once for each rotation of the shaft. Said actuator may be of any suitable form or construction, depending upon the specific nature of the service to be performed thereby, but as

shown herein, it is preferably made as a roller, either a ball or a disk, and free to roll on a plurality of axes at least one of which is parallel to the axis of the shaft. The actuator will be understood, therefore, as being effective to perform a certain function when occupying one runway, but when shifted to the opposite runway during the next rotation of the shaft, will be idle or inactive with respect to that particular function.

More specifically and with reference to Figs. 2, 3 and 4, the invention includes what may be termed a cam wheel 10 secured to a main shaft 11 and is rotated therewith as, for instance, in the direction of the arrow on Fig. 2. Said wheel 10 pertains to one of the cylinders 12 of the engine and is designed as shown for the purpose of controlling the admission of hydrocarbon into the cylinder through a valve represented at 13, Fig. 1. The device illustrated having four valves, it will, of course, be understood that the cam wheels will be of like number and so arranged as to operate upon said cylinder valves in succession as usual in engines of this type. A specific description of one of the cam wheels and the operation thereof will be understood as being applicable to all of them.

The wheel 10 is provided with a pair or plurality of runways which extend around the same in substantially parallel relation, means being provided, however, for communication from one runway to the other at stated times. These runways may be made of any suitable form or character, but as shown, they consist of a pair of grooves 14 and 15 separated from each other throughout the major portion of the circumference of the wheel by a rib 16.

At 17 is a gap in the rib 16 whereby the grooves have communication with each other under certain conditions hereinafter set forth. The runway 14 is formed with a cam 14^a, but the runway 15 is circular or of uniform radius from the axis of the shaft 11 throughout. The purpose of the runways is to coöperate with an actuator which operates in said runways in alternation, the actuator being operated for a certain purpose by the cam 14^a when occupying the runway 14, but when the actuator is at the runway 15 it will be idle during the next successive rotation of the shaft.

The actuator may be of any suitable form or construction, but as illustrated herein it is preferably in the form of a roller whereby it coöperates with the grooved member by rolling instead of sliding friction. The roller may be a ball or it may be a wheel or disk 18. In either event the actuator is shiftable laterally of the grooved member from one runway through the gap 17 to the other runway once for each rota-

tion of the shaft. Said shifting is practically in a direction parallel to the axis of the shaft. The shifting or transfer of the actuator from one runway to the other is effected automatically during the operation of the engine. As shown in Figs. 2, 3 and 4, the cam wheel rotates with the shaft and the actuator is relatively stationary but for the aforesaid shifting. In order to effect the shift or transfer, I employ a switch 19 pivoted at 20 in the line of the rib 16 and the pivot being preferably radial of the shaft 11. The point 19' of the switch spans one runway causing the actuator to shift from such runway to the other, and coming into contact with the heel 19'' of the switch, the actuator will cause the switch to be thrown so as to span the runway into which the actuator has just come. The switch is temporarily maintained in the position into which it is thrown by the actuator by any suitable means as, for instance, by a spring pressed ball 21 coöoperating successively with a pair of sockets 22 in said heel and on the opposite side of the pivot axis 20 from the point 19 of the switch.

By virtue of the cam 14^a in one of the runways, the actuator 18 is moved radially outward from the axis of the shaft 11, such movement being effective to produce any suitable mechanical result. For the purpose of actuating the valve 13 the actuator is journaled in one end of a lever 23 journaled at 24 on an axis parallel to the axis of the shaft 11, and when the actuator is forced in one direction by the cam 14^a, the opposite end of the lever is caused to be moved in the opposite direction, shown as upwardly, forcing a bar 24' upwardly to open the valve against the tension of a spring 25. The normal tendency of the spring is to seat the valve and maintain the actuator in constant coöperation with one runway or the other. The rod 24' is guided at 26 for reciprocation in a substantially fixed position. In order, therefore, for the shifting of the actuator to be accommodated in its support in the casing 27, the lever 23 is journaled on a turntable 28 pivoted on a substantially vertical axis 29 in said casing. Likewise the actuator 18 is journaled in a turntable 30, the axis of which is substantially at right angles to the axis of the wheel 18. It will be apparent, therefore, that the actuator will not only be free to follow the direction of the runways and the wheel because of the plurality of axes, but also the opposite end of the lever 23 will be free to oscillate laterally for coöperation with the lower end of the rod 24'. To relieve the friction at this point, a roller 31 coöperates with a wear plate 32, the roller being carried by the rod and the plate by the lever 23. It will be apparent from the description thus far that the cam wheel 10

will cause, through the actuator and parts between it and the valve, an actuation or opening of the valve during one rotation of the main shaft, while in the next rotation 5 the actuator will occupy the circular runway 15 and the valve will remain closed.

The same principle of operation is carried out in a slightly different form with reference to the ignition timer illustrated in Figs. 10 5, 6 and 7, wherein the actuator consists of a ball 18' which has constant coöperation in a groove 33 in a sleeve 34 connected in any suitable manner for rotation with the engine shaft 11. The actuator 18', as in the previous 15 construction, is shiftable laterally of said sleeve or longitudinally of the axis of the shaft once for each rotation of the shaft and hence coöperates in alternation with a pair of runways 14' and 15' formed as grooves 20 extending around the axis of the shaft in an annular member or sleeve 10'. In this special construction the grooved member 10' is relatively stationary and the actuator revolves around within the same because of the 25 rotation of the shaft and sleeve 34. A switch 19 similar in form and function to the aforesaid switch coöperates with such runways so as to cause the automatic shift of the actuator 18' through the gap 17 at each rotation 30 of the main shaft.

While the sleeve 10' is described as being relatively stationary, it is to be understood that it is adjustable slightly circumferentially of the shaft through the lever 35 for the purpose of varying the time of ignition of the several engine cylinders. The illustration being part of a four-cylinder engine of the four-cycle type, I provide for the ignition a series of contacts so that the several 40 cylinders will be fired in succession, each cylinder being fired once for each two rotations of the main shaft. As shown especially in the diagram of Fig. 7, I provide four contact buttons 36, one for each cylinder, and at 37 I show one contact button common to all of said cylinders. I employ a pair of cams 38 carried at diametrically opposite positions by the shaft or some part carried by the shaft, and these cams 38 engage the button 37 in succession while the 45 main shaft is rotated. During the moment of contact, therefore, between the button 37 and one of the cams 38, the actuator 18' in one of the runways 14' or 15' will be in contact 50 engagement with one of the two buttons 36 in that particular runway. When the shaft makes a half rotation, the actuator will engage the other button 36 in the same runway while the opposite cam 38 will be in engagement with the button 37 so that two 55 of the cylinders will be fired during each rotation of the main shaft. It will be noted, therefore, that the actuator will be ineffective during such one rotation of the main 60 shaft with respect to the other runway and

the two cylinders pertaining thereto. At the end of this particular rotation, however, the actuator 18' will be shifted by coming into engagement with the switch 19, coming first into engagement with the point thereof and finally with the heel thereof, causing the switch to be thrown so as to guard the opposite runway. The actuator then will be effective with the two contact buttons 36 in succession in this second runway and second 70 rotation of the shaft. 75

Any suitable system of wiring or insulation may be availed of to carry out this ignition mechanism in the manner above set forth, it being understood, of course, that each of the buttons engaged either by the actuator or cams 38 will be spring operated and adapted for electric wiring for the purposes set forth. The electrical connections will include the plug 36' arranged at any 80 suitable place so as to have connection at all times with the actuator 18' through the member 10'. 85

Having thus described my invention, I claim as new and desire to secure by Letters 90 Patent:—

1. In an engine, the combination of a rotary shaft, a grooved member connected to the shaft for rotation therewith, an actuator associated with the grooved member, and 95 means acting upon said actuator causing the actuator to shift laterally of said member at each rotation of the shaft, said shifting means including a pivoted switch coöperating with the actuator, the axis of the 100 pivot being substantially radial with respect to the axis of the shaft, the heel of the switch being provided with a plurality of sockets, and a sprung pressed ball coöperating with said sockets in alternation to lock 105 the switch temporarily in either position to which it may be thrown by the actuator.

2. In an engine, the combination of a crank shaft, cylinder mechanism, valve mechanism to control the operation of the 110 cylinder mechanism, said valve mechanism including a reciprocating rod, a cam member secured to the crank shaft and having a plurality of substantially parallel grooves extending around the periphery thereof, one 115 of said grooves being circular and the other being provided with a cam, there being a communication provided from one groove to the other, and an actuator for said reciprocating rod, said actuator including a roller 120 operative in said grooves in alternation, and a lever pivoted intermediate its ends and having one end coöperating with the end of said rod and having said roller journaled in the other end thereof, substantially as set 125 forth.

3. The herein described actuating means for internal combustion engines, the same comprising a cam member having a pair of peripheral grooves, one of said grooves be- 130

- 4
- ing circular and the other being provided with a cam portion, there being provided communication from each of said grooves to the other, a reciprocating rod adjacent said 5 cam member, a turntable mounted for partial rotation around a fixed axis, and a lever mounted on an axis at right angles to said turntable axis, one end of said lever being in contact with said rod, and a member connected to the opposite end of the lever and operative in alternation in said grooves, said member when in coöperation with the cam groove serving to reciprocate the rod, substantially as set forth.
- 10 15 4. In an actuating device for internal combustion engines, the combination of a crank shaft, a cam member connected to and rotated by said shaft, said cam member having a plurality of peripheral grooves, one 20 of the grooves being concentric with the shaft and the other being in part eccentric thereto, there being provided a communication from each of said grooves to the other, a reciprocating rod adjacent the cam member, a turntable mounted for limited rotation around a fixed axis, a lever pivoted on said turntable on an axis at right angles to the turntable, and parallel to the crank 25 shaft, one end of said lever being in communication with one end of said rod, and a roller journaled in the opposite end of said lever and coöoperating in alternation with said concentric and eccentric peripheral grooves, substantially as set forth.
- 30 35 5. The combination with a cam member and means to rotate it, said member having concentric and eccentric peripheral grooves,

of a reciprocating member adjacent the cam member, a lever mounted for oscillation around a plurality of axes at right angles 40 to each other, one end of said lever being in contact with the said reciprocating member, a turntable mounted in the other end of said lever, and a disk roller journaled in said turntable on an axis substantially at right 45 angles to the axis of the turntable and co-operating in alternation with the aforesaid grooves.

6. In mechanism of the class set forth, the combination of a shaft, an annular member surrounding the shaft and having formed therein a pair of grooves, an actuator comprising an antifriction roller operating in said grooves in alternation, a switch pivoted on an axis substantially radial of 50 the shaft between said grooves, the grooves being separated by a rib extending from one end of the switch around the member to the other end of the switch, said switch having a point acted upon first by the roller and having a heel subsequently acted upon by the actuator, and means acting between one end of said rib and the heel of the switch to temporarily lock the switch in the position in which it is thrown by the actuator, substantially as set forth.

In testimony whereof I have signed my name to this specification in the presence of two subscribing witnesses.

PAUL SUMBLER.
